VACUUM PUMP

Cyrus Howard Hapgood, Nutley, N. J., assignor
to The De Laval Separator Company, New
York, N. Y., a corporation of New Jersey

Application August 7, 1928, Serial No. 297,950

6 Claims. (Cl. 230—207)

The type of vacuum pump to which the present invention is particularly applicable comprises a housing, a hollow rotor within and eccentric to the housing, an air inlet port to, and an air outlet port from, the air space between rotor and housing, slideable vanes carried by the rotor and arranged radially to the rotor shaft and which extend into said air space and contact with the housing during the rotation of the rotor, a driving shaft to which the hollow rotor is secured, and a driving pulley on the shaft. Vacuum pumps of this character are disclosed in the Leitch Patent No. 1,367,554, dated February 8, 1921, the Hall Patent No. 1,374,650, dated April 12, 1921, and 15 patents issued to me No. 1,637,484, dated August 2, 1927, and No. 1,684,395, dated September 18, 1928.

The objects of the present invention are to insure a continuous circulation of oil through the pump, the maintenance of a constant and predetermined film of oil within the rotor chamber, and the prevention of leakage from the interior to the exterior of the pump.

A preferred embodiment of the invention is shown in the drawings, in which—

Fig. 1 is a longitudinal sectional view of the pump on the line 1—1 of Fig. 3.

Fig. 2 is an end view of the pump with the end cover plate removed.

Fig. 3 is a section through the pump on the line 3—3 of Fig. 1.

Rotor *a* is splined on a shaft *c* extending through a housing *b*. The rotor has slots through which wings or vanes *d* extend into the air compression space between rotor and housing and into contact with the inner circumferential wall of the housing, these vanes sliding toward and from the shaft in the rotation of the rotor, which is eccentrically disposed with relation to the housing.

Keyed to the shaft *c* is a driving pulley *e*.

In each end wall of the housing is an internal recess in which is fitted a shaft bearing. The bearing *f* nearest the driving pulley is preferably of the roller type while the other bearing *g* is preferably of the ball type.

Beyond bearing *f* shaft *c* extends through a stuffing box and an end plate *h* closing a chamber *i* formed at the end of the housing. The stuffing box comprises discs *k*, *k'*, respectively pressed, by a coil spring *m*, against the housing wall or web adjacent bearing *f* and against the end closure *h*. The shaft *c* may have ample play in the housing wall and in closure *h*, but the hubs of the disc *k*, *k'*, have a turning fit on the shaft.

This construction allows proper oiling of the

bearings, and if it does not necessarily exclude some leakage beyond disc *k*, any oil leaking therethrough will not escape to the outside of the pump, as hereinafter explained.

Beyond bearing *g* shaft *c* extends into an end chamber *n* closed by an end plate *o*. The end of the shaft that projects into chamber *n* carries a pinion *p* which engages a gear wheel *r* on a counter-shaft *s*. The gear wheel has formed on its outer face an arcuate rib or cam *t*. Secured to end plate *o* is a bracket *u* carrying, insulated therefrom, a contact *v*, connected with one pole of an electric circuit. Bracket *u*, which is connected with the other pole of the circuit, carries a pivoted contact arm *w*. A spring *x* normally holds arm *w* in contact with contact *v*. During part of the revolution of gear wheel *r*, cam *t* engages arm *w* and maintains it out of engagement with contact *v*. Thereby the electric circuit is alternatively opened and closed and electric pulsations are transmitted to a milking machine unit (not shown).

While the driving connections from the pump shaft to the electric pulsator form no part of the present invention, the adaptation of the pump to this purpose, when the pump is used to establish a vacuum in a milking machine, is one of its important uses; and the adaptability of the oiling provisions hereinafter described to the lubrication of the driving means between the pump shaft and the electric pulsator will be apparent from the description to follow.

The lower part of chamber *n* functions as an oil reservoir. The housing wall separating this chamber from the interior of the rotor is provided with an opening 10 through which the oil flows from chamber *n* into the interior of rotor and, when the pump is not in operation, fills the rotor to almost the level of the shaft *c*. In the same wall of the housing, above shaft *c*, are one or more large openings 11 which, together with the opening 12 around the axis in the opposite wall of the rotor housing, allows free circulation of air through the interior of the rotor from and to the open spaces within the housing beyond the end walls of the rotor chamber. One of these openings 11 is extended, at its rear outer edge, at 13, nearly, but not quite, to the inner circumferential wall of the rotor, being less distant than opening 10 from such wall. Thus, the edge of opening 13 nearest the circular inner wall of the rotor may be about one-sixteenth of an inch distant from said wall. The lower edge of hole 10, which is below and in vertical alignment with the axis of shaft *c*, may be 110

about three-sixteenths of an inch distant from said wall.

Opening to an air-suction pipe (not shown) is an air inlet 30 communicating with a long arcuate air chamber 31. The inner wall of the chamber is a short distance within the bore of the housing, leaving a narrow elongated arcuate orifice 32 for passage of air from chamber 31 to the space between the rotor and housing bore. 5 There may be two of these air chambers connected by a cross passage 33 into which the air inlet 30 directly opens. On the other side is an air outlet 34 from the air space between rotor and housing. This outlet, as shown by the arrow, 10 communicates with the outlet 35 to which is threaded an air exhaust pipe (not shown). The arrangement of air passages forms no part of the present invention and therefore is not required to be shown in more detail and is set forth fully in certain of the prior patents hereinbefore mentioned, e. g., No. 1,637,484.

When the pump is put into operation, centrifugal force throws the oil in the interior of the rotor out of such interior through the opening 13 into chamber *n*. This operation continues until there is left a film of oil not substantially greater in thickness than the shortest radial distance (which has been assumed to be one-sixteenth of an inch) between the outer edge of opening 13 and the inner wall of the rotor chamber. A fresh supply of oil is, however, continually entering the rotor from chamber *n* through the opening 10, so that discharge of oil, at a limited rate, from the rotor, proceeds continuously through the opening 13 into chamber *n*. In order to provide a plentiful supply of oil, the lower part of chamber *n*, comprising the oil reservoir, is extended in length as shown in Fig. 2, and provided with a filler-opening 14. A sight glass 15 allows visual 40 inspection of the interior.

The above construction insures a continuous circulation of oil and the maintenance of a desired volume of oil within the rotor chamber.

While escape of oil from the pump would be impossible if the stuffing box were oil-tight, the possibility of leakage of oil through both discs *k* and *k'* is guarded against by placing the stuffing box in the chamber *i*, hereinbefore mentioned, formed on the housing. This chamber communicates with the air compression space of the rotor through a small opening 20, the preferred location of which is best shown in Fig. 3. At this point in the air compression space, there is a vacuum of about two to three inches, and there is consequently a similar low vacuum in chamber *i*. Atmospheric pressure, therefore, prevents leakage of oil around shaft *c* through disc *k'*. By thus connecting the suction passage 20 from the chamber *i* with the air compression space of the rotor chamber and at a point where the vacuum is comparatively low, instead of connecting it with the suction side of the pump, leakage of oil is prevented without affecting the volumetric efficiency of the pump.

Having now fully described my invention, what I claim and desire to protect by Letters Patent is:

1. In a vacuum pump, the combination of a pump housing containing a substantially cylindrical rotor chamber having end walls and an adjacent chamber providing an oil reservoir, a driving shaft extending through the pump housing and rotor chamber, a rotor within the rotor chamber and mounted on the shaft so as to turn therewith, there being an oil discharge opening 75 in an end wall of the rotor chamber the minimum

distance between whose outer edge and the inner circular wall of the rotor is relatively small so as to provide a film of oil within the rotor of limited thickness, and an oil inlet through which oil flows from the oil reservoir to the interior of the rotor to maintain a constant circulation of oil through the interior of the rotor.

80

2. In a vacuum pump, the combination of a pump housing containing a substantially cylindrical rotor chamber having end walls and an adjacent chamber providing an oil reservoir, a driving shaft extending through the pump housing and rotor chamber, and a rotor within the rotor chamber and mounted on the shaft so as to turn therewith, there being an oil discharge opening in an end wall of the rotor chamber the minimum distance between whose outer edge and the inner circular wall of the rotor is relatively small so as to provide a film of oil within the rotor of limited thickness, and an oil inlet opening between the reservoir chamber and the interior of the rotor below said shaft whose outer edge is spaced a somewhat greater distance than the oil discharge opening from the inner circular wall of the rotor.

85

3. In a vacuum pump, the combination of a pump housing containing a substantially cylindrical rotor chamber having end walls and an adjacent chamber providing an oil reservoir, a driving shaft extending through the pump housing and rotor chamber, and a rotor within the rotor chamber and mounted on the shaft so as to turn therewith, there being an opening in an end wall of the rotor chamber and an oil inlet between said reservoir chamber and the interior of the rotor below said shaft, the outer edge of said oil inlet being spaced a greater distance from the inner circular wall of the rotor than the minimum distance of said opening from the inner circular wall of the rotor, said opening comprising an arcuate slot whose outer end edge is extended outward and through which oil is discharged to maintain a thin film of oil on the inner circular wall of the rotor and a constant circulation of oil through the rotor.

90

4. In a vacuum pump, the combination with a pump housing containing a rotor chamber and another chamber providing an oil reservoir, a driving shaft extending through the pump housing and rotor chamber, and a rotor within the rotor chamber and mounted on the shaft so as to turn therewith, of bearings inside the pump housing between said housing and the shaft, means to circulate oil from within the housing through the rotor and back to within the housing, a driving element secured to said shaft outside the housing, and an auxiliary chamber at the end of the housing nearer said driving element and in communication with the corresponding bearing, there being a passage between the auxiliary chamber and the air compression space of the rotor chamber, said passage being so located as to maintain in the auxiliary chamber a pressure which is sub-atmospheric but substantially higher than the sub-atmospheric pressure at the intake of the pump.

100

5. In a vacuum pump, the combination with a pump housing containing a rotor chamber and another chamber providing an oil reservoir, a driving shaft extending through the pump housing and rotor chamber, and a rotor within the rotor chamber and mounted on the shaft so as to turn therewith, of bearings inside the pump housing between said housing and the shaft, means to circulate oil from within the housing through the

5 rotor and back to within the housing, a driving element secured to said shaft outside the housing, means providing an auxiliary chamber at the end of the housing nearer the driving element and in communication with the corresponding bearing, discs within said chamber closely fitting the shaft, and elastic means between such discs holding the same against the end walls of the last named chamber, there being a passage 10 between the auxiliary chamber and the air compression space of the rotor chamber, said passage being so located as to maintain in the auxiliary chamber a pressure which is sub-atmospheric but substantially higher than the sub-atmospheric 15 pressure at the intake of the pump.

6. In a vacuum pump, the combination with a pump housing containing a rotor chamber and another chamber providing an oil reservoir, a driving shaft extending through the pump hous- 20

80 ing and rotor chamber, and a rotor within the rotor chamber and mounted on the shaft so as to turn therewith, of bearings inside the pump housing between said housing and the shaft, means to circulate oil from within the housing through the rotor and back to within the housing a driving element secured to said shaft outside the housing, means providing an auxiliary chamber at the end of the housing nearer the driving element and in communication with the corresponding bearing, and a stuffing box in said chamber surrounding the shaft, there being a passage between the auxiliary chamber and the air compression space of the rotor chamber, said passage being so located as to maintain in the auxiliary chamber a pressure which is sub-atmospheric but substantially higher than the absolute pressure corresponding to the partial vacuum at the intake of the pump.
